AUTOMOBILE OR SIMILAR ARTICLE

Dallas R. Lamont, New York, N. Y.

Application July 18, 1955, Serial No. 37,022

Term of patent 14 years

(Cl. D14—3)

Figure 1 is a view in perspective showing an automobile or similar article embodying my new design;

Figure 2 is a perspective of the left-hand portion of Figure 1, showing the design of the present invention in greater detail; and

Figure 3 is a perspective view, taken on a larger scale, of one of the trim elements, per se, shown in Figures 1 and 2, as viewed in perspective from a direction opposite to that of Figures 1 and 2.

The dominant features of my design reside in those portions shown in solid lines.

I claim:

The ornamental design for an automobile or similar article, substantially as shown and described.
